CLAIM

The ornamental design for a connector of a wall mounting base for a camera device, as shown and described.

DESCRIPTION

FIG. 1 is a bottom, front, right side perspective view of a connector of a wall mounting base for a camera device showing our new design;

FIG. 2 is an enlarged perspective view without environment thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The evenly spaced broken lines in FIGS. 1–8 depict portions of the connector of a wall mounting base for a camera device that forms no part of the claimed design. The additional evenly spaced broken lines only seen in FIG. 1 depict environment that forms no part of the claimed design.

The dash-dot lines in FIG. 1 marking the area FIG. 2 for enlarged detailed views in FIGS. 2–8 are for annotative purposes and form no part of the claimed design.
